United States Patent

Des. 240,113
Patented June 1, 1976

240,113

CONTAINER FOR PULVERULENT MATERIALS

George R. Conrad, Chicago, Ill., assignor to Blue Cross Laboratories, Inc., North Hollywood, Calif.

Filed Oct. 24, 1974, Ser. No. 517,725

Term of patent 14 years

Int. Cl. D9—01

U.S. Cl. D9—146

FIG. 1.

FIG. 2.

FIG. 3.

FIG. 4.

FIG. 1 is a perspective view of a container for pulverulent materials showing my new design;

FIG. 2 is an elevational view showing the side opposite that seen in FIG. 1;

FIG. 3 is a top plan view; and

FIG. 4 is a bottom plan view.

I claim:

The ornamental design for a container for pulverulent materials, as shown.
